UNDERWATER HOUSING FOR A CAMERA OR SIMILAR ARTICLE

Charles F. Soumar, Marathon, Fla., assignor to Underwater Photographic Service, Inc., Marathon, Fla., a corporation of Florida

Filed Nov. 15, 1965, Ser. No. 88,082

Term of patent 14 years

(Cl. D61—1)

FIG.1

FIG.2

FIG.3

FIG.4

FIG.5

FIG.6

FIG. 1 is a top plan view of an underwater housing for a camera or similar article, showing my new design;

FIG. 2 is a front elevational view;

FIG. 3 is a rear elevational view;

FIG. 4 is a bottom plan view;

FIG. 5 is a right side elevational view; and

FIG. 6 is a left side elevational view thereof.

The drawing figures are diagonally lined to indicate transparency.

I claim:

The ornamental design for an underwater housing for a camera or similar article, as shown and described.
